UNITED STATES PATENT OFFICE.

DANIEL L. F. CHASE, OF SOMERVILLE, MASSACHUSETTS.

STEAM-GOVERNOR.

SPECIFICATION forming part of Letters Patent No. 245,277, dated August 9, 1881.

Application filed November 19, 1880. (Model.)

To all whom it may concern:

Be it known that I, DANIEL L. F. CHASE, of Somerville, Middlesex county, Massachusetts, have invented a new and useful Improvement 5 in Steam-Governors; and I hereby declare that the following specification and the accompanying drawings give a full and correct description of the same.

My present invention is an improvement upon 10 the steam-governor for which I already hold Letters Patent No. 160,572, March 9, 1875, and No. 162,219, April 20, 1875; and it consists in a new form and arrangement of the valves, springs, &c., so as to secure greater efficiency, 15 durability, and cheapness.

Figure 1 is a side view of the machine, with a partial vertical longitudinal section. The part of this drawing to the right of the section, consisting of the cover to the case A, bracket 20 for supporting the shaft, packing-box, pulley, &c., are shown only in outline, and are not lettered nor described, because they do not directly concern the present invention. Fig. 2 is a partial vertical cross-section viewed from 25 the side A, Fig. 1. Fig. 3 is similar to the internal part of Fig. 2, but without any section, and with the valves opened out so as nearly to close the ports.

I retain the general principle of my original 30 patent first above mentioned to the extent of using a chamber or case which contains a centrifugal mechanism consisting of a hollow revolving steam conductor or flier, a pair of centrifugal valves, and a spring or springs acting 35 on said valves in opposition to the centrifugal force.

Referring to the drawings, A denotes the cylindrical case; B, the inclosed revolving flier; V V, the valves, and C the spring.

40 The central part of the flier B is a steam- passage continuous with the inlet of the case at A, and the steam, after entering the flier, passes through the hollow arms, the ports O O, and then out of the case at the bottom.

45 In my former patent the hollow arms constituting the valve-seats were made to support and guide the valves, and consequently, for ease of construction, were made preferably of cylindrical form. This plan was found to cause 50 undue friction and a tendency to cramp if the two springs were not of the same strength. I

now make the hollow arms each with two plane parallel valve-seats, and the valves, being box-shaped, fit over each side of the hollow arms and oscillate on their seats, each valve being 55 supported by a single pivot near their ends, so as to move in arcs of circles. In Fig. 1 the upper arm and its valve V V are shown in section, the section being slightly inclined from the vertical to suit the inclined position of the 60 steam-passage. (Shown at B in the upper part of Fig. 2.) The lower arm, B, and valve V, Fig. 1, are shown in elevation, as seen from the right of Fig. 2. Supposing the governor to be in the position shown in the figures, the 65 two pivots D D, upon which the valves V V swing, Figs. 2 and 3, are both in a vertical plane on one side of the axis of revolution, so that a large part of the weight of the valves may be actuated by centrifugal force in a direction to close the ports O O. Also, in the 70 plane of the pivots D D the valves have projections extending toward each other and interlocking in a knuckle-joint, E, so that they are obliged to move together. Fig. 2 shows 75 the valves V V closed together, so as to uncover the ports O O, while Fig. 3 shows the valves opened out, so as nearly to close the ports.

Instead of the two hollow arms and box- 80 valves described, I may use two pairs of hollow arms with ports opening inward toward each other and solid block-valves playing between.

The spring C employed is nearly semicircular in form, (commonly called a "C-spring.") 85 It embraces about one-half the periphery of the valves, including their pivoted ends, and is so attached to said valves with reference to the pivots that it tends to press them together in opposition to the centrifugal force. 90

I prefer the C-spring, partly for its adaptation to the cylindrical form of the machine and partly for its "graduating" properties. "Graduation" in a steam-governor means that a given change of speed causes a decreasing change 95 of valve-opening as the valve approaches closure. The more the C-spring is straightened out (applying the strain as I do) the less it will yield to a given amount of additional strain, which is the effect desired in connection with closing the governor-valves. A spiral spring stretches a fixed amount when a 100

given additional strain is applied without reference to its previous tension.

My **C**-spring is preferably a wide strip of steel or other metal with a hole near each end, 5 which holes receive suitable screws or pins on the valves. This method of attachment, though not essential, is convenient for the following purpose: If it is desired to change the speed of the engine by altering the tension of the 10 spring, this object may be accomplished by using adjusting-screws **S S**, as shown. The spring **C**, after slipping over the outer ends of the screws **S S**, rests upon shoulders on the same, so that by turning the screws outward 15 the tension is increased, and vice versa.

The adjusting-screws **S S** may be altered by removing the internal parts of the governor from the case; or, as I prefer, they may be reached through a suitable hole in the case by 20 removing a cap or plug, **F**.

It will be seen that my centrifugal valves, in combination with adjusting-screws, may be used with various kinds of springs. If no change of speed is required, I would use fixed 25 pins or studs instead of the screws **S S**.

Having sufficiently explained my invention, what I claim as my invention, and desire to secure by Letters Patent, is—

1. In a steam-governor composed of a chamber or case inclosing a centrifugal mechanism, 30 the combination of a hollow revolving flier with a pair of centrifugal box-valves, said valves being pivoted, jointed together, and actuated in one direction by a spring or springs, substantially as described, and for the purposes 35 explained.

2. In a steam-governor composed of a case inclosing a centrifugal mechanism, the **C**-spring, in combination with a pair of centrifugal valves, said valves being pivoted to a hollow 40 revolving flier, and the whole arranged substantially as described, and for the purposes explained.

3. A steam-governor composed of a chamber inclosing a centrifugal mechanism, said 45 mechanism consisting, essentially, of a hollow revolving flier, a pair of centrifugal valves, and a spring or springs provided with adjusting-screws, all arranged substantially as described, and for the purposes explained.
